(57) **CLAIM**

The ornamental design for a caddy for a toilet cleaning handle, as shown and described.

DESCRIPTION

FIG. 1 is a perspective view showing the new design for a caddy for a toilet cleaning handle;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The portions of the caddy for a toilet cleaning handle in the Figures shown in broken lines are included to show features that form no part of the claimed design.

1 Claim, 7 Drawing Sheets
